SAFETY RAZOR

Horace L. Kent, Brooklyn, N. Y.

Application September 26, 1933, Serial No. 691,055

4 Claims. (Cl. 30—12)

This invention relates to safety razors, and more particularly to safety razors having a power driven element coacting with the blade to enable the shaving to be done dry. The invention also contemplates a safety razor of the type referred to, combined in one instrument with any usual or preferred construction of the safety type adapted for wet shaving.

The razor of my invention embodies a roller having thereon a helical thread which coacts with the razor blade in shaving. I am fully aware that many attempts have been made to provide a practical razor embodying a flexible blade and a roller of the type just mentioned. However, all such constructions have heretofore failed to be practical due to the fact that in shaving, such razors have caught the skin between adjacent turns of the thread. The razor of my invention, however, overcomes this defect of the prior art, chiefly due to the fact that adjacent turns of the roller thread in my construction are sufficiently close together and/or the thread is sufficiently shallow to avoid catching the skin between adjacent turns of the thread. In other words, by making the thread sufficiently shallow or by providing a thread the adjacent turns of which are sufficiently close together, or both, I provide a razor of the type mentioned, which is entirely practical and which provides a very satisfactory dry shave.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a plan view of a safety razor embodying my invention.

Fig. 2 is an end view.

Fig. 3 is a view similar to Fig. 2 but with the cap removed and the blade broken away.

Fig. 4 is a fragmentary side view, partly in section.

Fig. 5 is a sectional view showing the ball bearing mounting of the roller which forms part of the razor; and

Fig. 6 is an enlarged view illustrating the contour of the thread.

Referring to the drawing for a more detailed description thereof, the numeral 7 indicates the razor handle which is interiorly threaded at its distal end and is screwed onto a threaded stem 8 of the cap 9, the threaded or distal end of the handle being tightened against the end of a tubular member 10 thru which the stem passes. A guard 12 provided with elongated slots 13 is adjustably mounted, relative to a roller 19, by means of screws 14 on extensions 15 of a trough 16. The adjustability of the guard 12 allows the blade to be adjusted relative to the roller as the blade wears. The adjustability of the guard together with the varying pressure which may be put on the blade by the coaction of the cap and the handle screwed thereto, is a novel construction and one which enables the user to keep the blade at a proper pressure on the roller as the blade is worn down by the sharpening action of the thread on the same. The guard 12 has a central oval aperture 12a thru which passes the threaded stem 8 attached to the handle. A two-edged blade 17 is held between the guard 12 and the cap 9, said guard having lozenge or diamond-shaped processes or raised portions 12b which fit into correspondingly formed apertures 11a in the razor blade to assist in keeping the latter in position. The guard 12 and the corresponding edge 30 of the blade are used in wet shaving.

Within the trough 16 is positioned the roller 19, which is hollow and which has a helical thread 19a which, when the roller is turned toward the corresponding edge of the blade 17, coacts or cooperates with that edge in shaving, enabling the shaving to be performed dry, that is to say, without lather or other beard moistening medium. The provision of a hollow roller is one of the features of my invention, providing as it does a lighter construction which allows for a lighter pressure on the skin during shaving. The thread 19a of the roller should not be too deep, nor adjacent turns thereof be too far apart, otherwise the skin will be caught between adjacent turns of the thread and the efficiency of the razor will be impaired. It has been found by experimentation that the depth of the thread may be approximately $\frac{1}{16}$ of an inch or less, while adjacent turns may be $\frac{1}{16}$ of an inch apart, or less. To improve the cutting efficiency of the cooperating razor edge and roller thread, the right hand side of the latter is undercut or cut inwardly to provide a rather sharp edge, as shown in Fig. 6.

The roller 19 has reduced ends which are 55

mounted in ball bearings 20 at the ends 16a of the trough 16 to reduce the friction to a very small quantity, one of said extensions 19b passing thru one of the end walls of the trough and 5 forming a shaft to which is to be attached a flexible shaft run by an electric motor for the purpose of rotating the roller 19 toward one of the cutting edges of the blade 17. The trough is provided adjacent its right hand end with an opening 16b thru which the finely cut hair is discharged by the action of the roller, this position of the discharge opening allowing the hair to be thrown out in such position that it does not fall upon the operator of the razor.

10 15 In order to provide an efficient razor and one having long life, it is very important that the roller and its bearings be made of rust proof material. The necessity for oiling, which is seldom thought of or done by the owner of the 20 razor, will thereby be avoided. In fact it is very desirable that all parts of the razor with the exception of the blade be made of rust proof material.

What is claimed as new is:

25 1. A safety razor comprising a body, and a handle, a guard for one edge of said body and disposed on said body and extending to one side of the handle, a flexible blade on said guard, means for holding said blade in position, a roller 30 having a peripheral thread adapted to coact with the other edge of said blade in shaving, a trough in which said roller is mounted, said trough being adapted to catch cut hair and having adjacent its bottom an outlet for the cut hair.

35 2. A safety razor comprising a body, a periph-

erally grooved roller rotatably mounted in the body, a guard disposed on the body in tangential relation to the roller, a blade seated upon the guard in fixed relation thereto, means for adjusting the guard to vary the position of the edge 5 of the blade with respect to the roller tangentially thereof, and clamping means for the blade to flex the latter and vary the position of its cutting edge radially of the roller.

3. A safety razor comprising a body, a roller rotatably mounted in the body, a guard seated upon the body, screws passing through elongated slots in the guard and entering the body, so that the guard may be adjusted tangentially of the roller, a blade seated upon the guard in fixed 15 relation to the latter, a cap engaged with the guard and having a threaded stem passing through the body, and a handle engaging the stem to retain the cap in place.

4. A safety razor comprising a body, a roller 20 rotatably mounted in the body, a guard seated upon the body, screws passing through elongated slots in the guard and entering the body, so that the guard may be adjusted tangentially of the roller, a blade seated upon the guard in fixed 25 relation to the latter, a cap engaged with the guard and having a threaded stem passing through the body, and a handle engaging the stem to retain the cap in place, the guard being formed with raised portions entering correspondingly shaped openings in the blade and the latter being flexible so that its cutting edge may be adjusted radially of the roller by varying the degree of clamping action of the cap.
